UNITED STATES PATENT OFFICE.

JOHN HAYS HAMMOND, JR., OF GLOUCESTER, MASSACHUSETTS.

MEANS FOR CHANGING THE INTENSITY OF SIGNALS IN RADIODYNAMIC RECEIVING SYSTEMS.

Application filed May 6, 1918, Serial No. 232,705. Renewed May 31, 1924.

This invention relates to means for reducing the intensity of strong signals produced through or pertaining to radiant energy, and in certain of its aspects is an improvement upon the invention disclosed in the joint application of myself and Emory Leon Chaffee, Serial No. 177,202, filed June 27, 1917.

In order that the principle of the invention may be readily understood, I have disclosed a single embodiment thereof and the mode best known to me for practicing the same.

In the drawings,—

Fig. 1 diagrammatically represents a receiving system having my invention applied thereto;

Fig. 2 diagrammatically represents a characteristic audion curve;

Fig. 3 diagrammatically indicates certain potential rises on the grid of the electron relay;

Fig. 4 is a diagrammatic representation of certain impulses obtained in the practice of my invention;

Figs. 5 and 6 diagrammatically indicate wing current fluctuations in the practice of my invention; and

Fig. 7 represents curves characteristic of the practice of my invention.

In accordance with my invention I provide means furnishing a leak, generally analogous to a resistance, but which is much more effective for strong signals than for weak ones, and thereby prevent the action of static or atmospheric disturbances or strong interference upon the receiving system.

Referring more particularly to the drawings, I have in Fig. 1 represented the primary winding of a transformer at 1, this winding being included in an open aerial receiving circuit comprising an antenna 2 and a ground 3. The secondary winding 4 of the transformer is included in a closed oscillatory circuit and is indicated at 5, a tuning condenser being designated by 6, and a stoppage condenser by 7. The said stoppage condenser is in series with the grid 8 or potential gradient changing means of an audion detector or thermionic valve, the evacuated tube whereof is indicated at 9, the plate at 10, and the heated filament or ionizing means at 11, a battery 12 being

provided for heating said filament 10. The grid 7, plate 9 and filament 10 are frequently termed "electrodes." Leading from the secondary winding 4 are conductors 13 and 14, the former of which leads to the grid 7 and has interposed therein the said stoppage condenser 6. The conductor 13 leads to the heated filament 10.

Shunted about the stoppage condenser 6 is what may be termed a variable or differential resistance or leak, which, considered as a by-pass, is much more effective for strong signals than for weak signals. This variable or differential resistance, leak or valve, as it may be termed, is generally similar to the disclosure in the said copending application of myself and Emory Leon Chaffee, and herein comprises an evacuated tube 14 having sealed therein a plate 15, a grid 16, and a heated filament 17, a heating battery 18 being provided for the latter. The plate 15 is connected to the conductor 12 by a conductor 19, and the heated filament 17 is connected to said conductor 12 by a conductor 20, the potentiometer 20 being preferably provided as diagrammatically indicated for fine adjustment of the functioning voltage of the apparatus. The conductors 19 and 20 are at the opposite sides A, B respectively of the said stoppage condenser 6.

The action of the said variable or differential resistance or leak need not be particularly described, since generally it is the same as that disclosed in the said copending application.

The said variable or differential resistance or leak provides a by-pass which allows the stoppage condenser 6 to discharge according to the potential strain produced across the plate 15 and the heated filament 17. The action of such variable or differential resistance or by-pass is to allow the charges of high potential produced in the stoppage condenser 6 by atmospheric disturbances to leak through said by-pass so that the positive charges travel from the plate 15 to the heated filament 17 and to the side B of the condenser 6, while the negative charges travel from the side B of the condenser 6 through the filament 17 to the plate 15, and thence to the side A of the condenser 6. This equalizes the sign of the charges on either condenser plate of

the said stoppage condenser 6 in such a way as to reduce the potential strain across said condenser.

The described effect occurs only when the voltage across the by-pass is of such value as to allow a discharge to take place through it. In order to facilitate such discharge, a positive potential is applied to the grid 16 by means of a battery 20 so as to steepen 10 the potential gradient and thereby conduce to a greater emission of negative electrons from the filament 17.

In Fig. 2 I have diagrammatically represented at 21 a characteristic curve of the audion having the grid 16. The abscissa represents the voltage applied to the grid 16, as indicated at 22, and the ordinate represents the value of the current flowing from the plate 15 to the heated filament 17, as indicated at 23. This curve is fairly representative of the class of three-electrode electron detectors that are fairly highly vac- 20 uized.

Extending from the plate 9 of the audion 25 tube 8 is a conductor 24, and extending from the heated filament 10 of such audion tube is a conductor 25 having therein a battery 26. The said battery 26 is connected with the electron detector so as to produce the so- 30 called flux current or plate current.

Operatively associated with the said conductors 24 and 25 is a tuned circuit containing a condenser 27 and an induction coil 28. The circuit containing the said condenser 27 35 and induction coil 28 is preferably tuned to an inaudible group frequency, for example, twenty thousand cycles per second. The inductance coil 28 is inductively coupled to an inductance coil 29 which is shunted by a con- 40 denser 30. Leading from the said inductance coil 29 are conductors 31 and 32. In the case assumed, the circuit containing the inductance coil 29 and condenser 30 is like- 45 wise tuned to twenty thousand impulses per second.

If high frequency oscillations be emitted 50 from the transmitter in groups of twenty thousand per second, and if the stoppage condenser 6 connected to the grid 7 be not short-circuited by the action of the said variable resistance or by-pass, there are obtained through the action of the audion tube 8 which constitutes an electron relay, im- 55 pulses of the character indicated at 33, 33 in Fig. 4. These impulses are rectified on account of the functioning of the electron relay 8 which has well known rectifying qualities.

On account of the storing of the charge 60 in the stoppage condenser 6, the individual high frequency oscillations will tend to add up on the grid 16 of the audion tube 14, thereby reducing the flux current or plate current through the said electron relay 8. 65 The rises of potential on the grid 16 will

occur as indicated at 33 in Fig. 4, and will have a slight superimposition of the individual high frequency oscillations. The effect, however, will be to produce through the inductance coil 28 unidirectional pulses 70 of current at the rate of twenty thousand per second, since the condenser 27 and the inductance coil 28 are in tune to this period. By means of resonance, strong oscillations will be produced in the circuit which will be 75 transmitted by induction to the circuit containing the inductance coil 29 and the condenser 30. This operative connection in the electron relay 8 is represented by the characteristic curve 21 in Fig. 2. 80

Let it be assumed that normally the plate current is at *a* on the said curve 21 and that with an in-coming signal it will be reduced to the point *d* on the said curve, such action taking place when the stoppage condenser 85 6 is in series with the grid 16 and the accumulation of the various high frequency oscillations is such as to produce a negative charge on the grid 16 which reduces the plate current in a well known manner to a 90 great extent.

When, however, the said variable resistance or by-pass functions so as to short circuit the stoppage condenser 6 and practically to eliminate the storing effect thereof, 95 then the potential rises on the grid 7 of the electron relay 8 as is best indicated by the diagrammatic representation 34 in Fig. 4.

In such case, the functioning is on the curve 21 in Fig. 2 from the point *b* to the point *c* (symmetrically about the point *a*), thus producing rapid diminution and rapid increases of the plate current, keeping exact step with the variations of the potential produced on the grid 7 by the individual high 105 frequency oscillations acting thereon.

Thus there will be in the plate circuit symmetrical fluctuations whose frequency is equal to that of the high frequency oscillations of the transmitting station. If now 110 the frequency of the oscillations of the transmitting station were equal to, say, one million per second, then the oscillating circuit containing the inductance coil 28 and the condenser 27, would constitute an impedance 115 to these unidirectional high frequency impulses which would be enormous. Therefore the circuit containing the inductance coil 28 and the condenser 27 would remain totally unaffected by such impulses, and would not transmit energy to the oscillatory circuit containing the inductance coil 29 and the condenser 30. 120

Thus, in a selective system which depends upon the use of a high frequency wave emitted at a specific group frequency, and having a receiving station operating through the joint action of the high frequency and its group frequency, the interference pre- 125 ventor herein disclosed produces a still fur- 130

ther degree of selectivity, inasmuch as it modifies the functioning or operation of the electron relay 8 and changes its action so that whereas previously it allows unidirectional impulses of twenty thousand per second to traverse it, it now allows unidirectional impulses of a million to traverse it.

The stoppage condenser 6 is alternately thrown in and out of action by the functioning of the variable resistance or by-pass and when it is thrown into action it allows an accumulation of the high frequency oscillations to take place, so that the true group effect, as illustrated at 33 in Fig. 4, passes 10 through the electron detector or relay 8 in the unidirectional pulsations of direct current. When the said condenser 6 is cut out, then no accumulation takes place in the grid 7 in the said electron relay, and the individual high frequency pulsations of current 15 are passed through the said electron relay 8, which, being entirely out of tune to the low frequency twenty thousand period circuit, cannot create in it oscillations to build 20 up its resonance.

When employing an audion detector in the old way with the stoppage condenser on the grid, that adjustment of the grid potential which gives the greatest response in the 25 plate circuit to the incoming groups of high frequency waves is the very adjustment which, when the stoppage condenser is short circuited, will give absolutely no response in the plate circuit to the groups. My invention 30 takes advantage of the said phenomenon and furnishes a leak for the stoppage condenser which does not become effective until voltage in excess of those encountered with the normal working signals are met with. 35 Heavy static shocks and forced interference 40 are allowed to get by this first audion with only little greater vigor than the normal working signals. In the case of randomly recurring shocks, such as those due to atmospheric static electricity, this is sufficient to 45 render them inappreciable in a subsequent tuned circuit.

In Figs. 5 and 6 respectively, I have diagrammatically indicated wing current fluctuations when the stoppage condenser is functioning normally and when said condenser is effectively short circuited.

In Fig. 7, I have shown curves characteristic of the use of my invention.

Having thus described one embodiment of my invention and the mode best known to me for practicing the same, I desire it to be understood that although specific terms are employed, they are used in a generic or descriptive sense and not for purposes of limitation, the scope of the invention being set forth in the following claims.

Claims.

1. A receiving system for radiant energy 65 comprising in combination with a closed os-

cillatory circuit responsive to electrical oscillations, a three element thermionic detector operatively connected therewith, of a grid condenser connected in series between said closed oscillatory circuit and said detector, a thermionic valve in shunt with said grid condenser and means for varying the functioning voltage of said shunt. 70

2. A receiving system for electrical impulses comprising a detector of electrical 75 impulses including a container, and ionizing means, potential gradient changing means, and a terminal arranged in said container, a circuit responsive to electrical impulses and connected to said potential gradient 80 changing means for controlling said detector, and a by-pass shunted around a portion of said circuit for protecting said detector from excessive impulses, said by-pass including a container, and ionizing 85 means, potential gradient changing means, and a terminal arranged in said last-mentioned container, a source of electric energy for heating said ionizing means, and a potentiometer in series with said source and 90 adjustable to vary the functioning voltage of said by-pass.

3. A system for receiving electrical impulses comprising a thermionic valve including a container, and ionizing means, potential gradient changing means, and a terminal enclosed in said container, a circuit responsive to electrical impulses and connected to said potential gradient changing 95 means for controlling said thermionic valve, and a by-pass shunted around a portion of 100 said circuit for protecting said thermionic valve from excessive impulses, said by-pass including a container, and ionizing means, potential gradient changing means, and a terminal arranged in said last mentioned 105 container, a source of electric energy for heating said ionizing means and a potentiometer in series with said source and adjustable to vary the functioning voltage of 110 said by-pass.

4. A receiving system for radiant energy comprising a detector, a closed, oscillatory circuit responsive to electrical oscillations and operatively connected with the input side of the detector, an impedance element connected in series between the oscillatory circuit and the detector and across which high potentials may be induced, a device connected in shunt with said element and having a resistance which is much less for differences of potential above a predetermined value than for smaller differences of potential, and means for varying the functioning voltage of said device. 115 120 125

5. A receiving system for radiant energy comprising a detector, a closed, oscillatory circuit responsive to electrical oscillations and operatively connected with the input side of the detector, a condenser connected 130

in series between the closed oscillatory circuit and the detector, a device permanently connected in shunt to said condenser and having by reason of its construction and without continuing external control a resistance which is much less for differences of potential above a predetermined value than for smaller differences of potential, and means for varying the value of the difference in potential at which said device functions to short-circuit the condenser.

6. A receiving system for radiant energy comprising a three-electrode thermionic detector, a closed, oscillatory circuit responsive to electrical oscillations and operatively connected with the input side of the detector, an impedance element connected in series between the oscillatory circuit and the grid of the detector and across which high potentials may be induced, a thermionic tube connected in shunt with said impedance element and acting to oppose less resistance to the passage of currents at high potentials than at low potentials, and means for varying the functioning voltage of said tube.

7. A receiving system for radiant energy comprising a detector, a closed, oscillatory circuit responsive to electrical oscillations and operatively connected with the input side of the detector, an impedance element connected in series between the oscillatory circuit and the detector and across which high potentials may be induced, a three-electrode thermionic tube connected in shunt with said impedance device and acting to oppose less resistance to the passage of currents at high potentials than at low potentials, means for impressing a constant positive potential on the grid of said tube as compared with the filament, and a variable resistance connected in series between the tube and said impedance device for varying the functioning voltage of the tube.

8. A receiving system for radiant energy comprising an impedance element across the terminals of which high potentials may be induced, and a by-pass for said element including a three-electrode thermionic tube having its plate and filament connected across the terminals of the element, a source of potential between the grid and filament of said tube, and means for varying the functioning voltage of the tube comprising a potentiometer connected in parallel with the filament and a connection between the potentiometer and one of the terminals of the element.

9. A receiving system for radiant energy comprising a detector, a source of energy on the input side of the detector, an impedance

element connected in series between said source of energy and the detector and across which high potentials may be induced, a device connected in shunt with said element and having inherently and without continuing external control a resistance which is much less for differences of potential above a predetermined value than for smaller differences of potential, and means for varying the functioning voltage of the device.

10. A receiving system for radiant energy comprising a detector, a source of energy on the input side of the detector in the form of a transformer having its secondary winding connected with the detector, an impedance element connected in series between said winding and the detector and across which high potentials may be induced, a device connected in shunt with said element and having inherently and without continuing external control a resistance which is much less for differences of potential above a predetermined value than for smaller differences of potential, and means for varying the functioning voltage of the device.

11. A receiving system for radiant energy comprising a three-electrode thermionic detector, a closed, oscillatory circuit responsive to electrical oscillations and operatively connected with the input side of the detector, an impedance element connected in series between the oscillatory circuit and the grid of the detector and across which high potentials may be induced, a device permanently connected in shunt with said element and having a resistance which in direct response to potentials impressed across its terminals is much less for differences of potential above a predetermined value than for smaller differences of potential, and means for varying the functioning voltage of the device.

12. A system for receiving radiant energy in the form of a series of high frequency waves modulated at a regular periodic group frequency above good audibility, comprising a detector, a closed, oscillatory circuit arranged on the input side of the detector and tuned to said high frequency, a closed oscillatory circuit connected with the output side of the detector and tuned to the group frequency, an impedance element connected with the input side of the detector and a device permanently connected in shunt with said impedance element for short-circuiting it for potentials above a predetermined value.

In testimony whereof I have signed my name to this specification.

JOHN HAYS HAMMOND, JR.
